UNITED STATES PATENT OFFICE

HARRY SWINGLEHURST, OF ORANGE, NEW JERSEY, ASSIGNOR TO SCOTT & WILLIAMS, INCORPORATED, OF NEW YORK, N. Y., A CORPORATION OF MASSACHUSETTS

PATTERN MECHANISM FOR AUTOMATIC KNITTING MACHINES

Application filed January 10, 1929. Serial No. 331,573.

This invention relates to devices for controlling and coordinating motions of parts in a pattern-controlled automatic machine for making textile fabrics, especially the motions relied upon for the timely adjustment or setting of agencies of a knitting machine required to be occasionally and seasonably operated during the production of each product or article being made; or the orderly performance of any predetermined cycle of useful activities of the parts of the mechanism to which it is applied.

The knitting instruments proper of hosiery knitting machines, for example, require to be differently positioned or actuated in an orderly and complex sequence to cause the performance upon them of operations on yarn supplied to make in order the parts of fashioned stockings, with or without decorative pattern, or other articles of hosiery. Artisans in this art are familiar with devices suitable to be controlled automatically for operating on needles of a series of needles to form progressive knitting waves, to change the relation of needles to operating cams for changes of length of stitch, to determine seasons of progressive knitting waves and seasons of reciprocatory knitting waves for fashioning; to determine the activity or inactivity of series only of the needles, to alter the relations to needles of sinkers or web-holders; to operate yarn-changing or splicing or clamping and severing devices, and to determine picking of needles into or out of action for widening or narrowing; or special operations for knitting articles of hosiery in discontinuous succession with welts and other special structures.

In circular knitting machines satisfactory devices for automatically determining and controlling the times and duration of continuous rotary motion or oscillatory reciprocating motion between needles, their actuating cams, and yarn-feed devices exist in several types. But the demand for further changes in one or more of the typical kinds of operation for automatic special function of the knitting devices grows with time, and usual pattern-controlling devices provide with great difficulty or not at all for any addi-

tions to the normal activities of the machine. It is customary in the art to provide pattern mechanism for determining the major and necessary machine activities as consequences of one revolution by intermittent angular advances of a main pattern shaft and consequent motion of connections to the machine agencies, usually worked by cams on a surface or surfaces moved with the shaft. Every change of activity thus requires a certain angular motion of the main pattern shaft; the number of changes capable of being made is limited to the summation of the angular motions severally required for each change; and one revolution is no longer sufficient to provide for enough motions for all of the changes required. Such a main pattern shaft is usually itself under the control of a continually and intermittently advanced primary pattern surface, usually a mutable-link chain worked by a ratchet at intervals of several revolutions of the needle-carrier, and serving to count knit courses between forward racks or angular advances of the main pattern shaft. No change can be provided for except at said intervals of multiples of revolutions.

These conditions have heretofore led to proposals of devices for transfer of operation of devices to be controlled to auxiliary movable surfaces bearing cams or other operating elements for connections to the parts to be controlled. The primary pattern chain has itself been utilized to work directly some of the parts to be controlled, as well as to determine motions of the main pattern shaft; and sundry auxiliary pattern surfaces have been arranged for independent operation to work particular groups of connections, such as series of yarn-fingers for yarn-changing to make stripes. The main pattern has been specially moved for timing at intervals of fractions of a needle-carrier revolution; for examples the United States Letters Patent to Robert W. Scott, No. 1,148,055 dated July 27, 1915 and No. 1,225,683 dated May 8, 1917 may be consulted. But none of the devices of the kind mentioned of which I am aware is free from the defect of making the orderly control of the devices to be operated dependent

on skilled operation. Since it is practically necessary to arrange for manual adjustment of the machine to pick up operation at any point in its set pattern of successive operations (in order to avoid waste when there has been a failure of performance, a replenishment of materials, or some adjustment), whenever the pattern indications depend on two or more pattern surfaces it is relatively easy for a careless operator to disturb coordination between them, so that the machine often does not perform as intended.

A principal object of this invention is to provide a pattern mechanism for knitting machines capable of controlling a plurality of different operations of the machine instruments during a predetermined cycle, in which motions of the main pattern shaft are conserved by delegating repeated subordinate or auxiliary operations to control by an auxiliary pattern surface or surfaces; and to provide for operating the main and auxiliary surfaces in such relation to each other that careless or ignorant interference with manually controllable agencies of the machine will not disturb the desired coordination of movement among the respective pattern surfaces. Another object of the invention is to provide for the control of controllable operative elements of the machine severally by two or more different pattern surfaces, so that the control of said elements may be by one or by another of said pattern surfaces, or by both in conjunction as desired. Another object is to provide, in a machine having a primary pattern surface movable at intervals of numbers of revolutions of a needle-carrier, means for operating a main and an auxiliary pattern surface at alternate intervals, the beginning of operation of either surface being controlled by said primary surface; the operation of either surface alone preventing the independent operation of the other until the completion of a predetermined cycle of motions by the pattern surface in operation shall have taken place. A further object of the invention is to provide, in a knitting machine intended to make heel or toe pockets by sequences of several different narrowing or widening operations, for controlling by an automatic pattern device switch cams, picker-controllers, motion-changing clutch devices, or other controllable parts concerned in making such a heel or toe, in such a way as to enable any useful number, more than one, of narrowing and widening operations to take place during making of heels or toes, and during minimum motions only, or complete suspension of motion, of the main pattern surfaces of the machine.

The invention will now be explained in connection with the accompanying drawings showing an embodiment in preferred forms only, and in which

65 Fig. 1 is a front elevation of an automatic

circular hosiery knitting machine exemplifying an application of the invention;

Fig. 2 is a right side elevation of devices shown in Fig. 1 on an enlarged scale;

Fig. 3 is a left side elevation of parts only of the device;

Fig. 4 is a detail in plan above the bed plate of the knitting head;

Fig. 5 is a detail left side elevation of parts shown in Fig. 4.

Referring now to Figs. 1 and 2, the illustrative embodiment of the invention is shown as adapted for use with the familiar Scott & Williams circular fashioning stocking knitting machine, but is applicable without change of character to other kinds of driving and controlling devices for other textile or other knitting machines. The machine illustrated is driven by a belt on one of the pulleys P or P^2 to either of which (or to a loose pulley P^2) the belt may be automatically shifted by a belt shipper, not shown, controlled by a cam drum 105 and sliding on rod 93. Pulleys P^2 and P are respectively fast to inner and outer concentric tubular shafts having their axial center at 32, Fig. 2. When pulley P is driven, a pinion, not shown, fast on its tubular shaft drives a larger plate-gear 65 fast on a secondary shaft 55 having a bearing in the machine frame, and fast on shaft 55 a gear larger than 65 meshes with a rotary driving pinion fast on tubular shaft 39, to drive shaft 39 at a higher rate than said shaft 39 is driven by the pulley P^2 which is fast on shaft 39. Said rotary driving pinion is integral with or attached to one member of a clutch, thus adapted to be rotated at different rates by pulley P or P^2 , the other member of which clutch is keyed to and slides on a solid driving shaft concentric with and having a bearing in tubular shaft 39.

This driving shaft, not shown, as usual carries a bevel gear for driving the driven element, such as the needle cylinder, of the knitting head, and has upon it a pinion 35 meshing with a gear sector 75 and integral with or attached to a clutch face adapted to engage the sliding element of the clutch when it is disengaged from the rotary-driven clutch face. Sector 75 is constantly oscillated about the stationary bearing shaft 76 by a pitman 70 from a crank pin 61 rotating with shaft 55 and taking over a crank pin 71 fast in sector 75. The bearing sleeve or hub of the sector 75 is extended at 78 to carry a crank pin 77 in a hole in a pawl 82, relied upon to actuate a toothed rack wheel 81 fast on the main pattern shaft 80. The hub of sector 75 also provides a seat for a crank pin 88, at an angular distance from pin 77 of nearly a right angle, which pin 88 takes into a hole in and actuates a pawl 87 relied upon to move the primary pattern surface, made as a mutable-link chain C , continually at intervals corresponding to back or idle strokes of

75

120

125

130

pawl 82. The chain C is moved by a sprocket 84 integral with or attached to the ratchet 86, loose on shaft 80, for pawl 87. The ratio of the gearing is usually such that sector 75 and the pawls 87 and 82 make each one complete oscillation to each four revolutions of the driving bevel gear and rotary parts of the knitting head.

When the sliding element of the clutch on the driving shaft is shifted to connect pinion 35 to said shaft, the knitting head may oscillate through an arc of approximately 365°, as driven by sector 75 and pinion 35.

The clutch may be shifted automatically by a sliding fork 92 having a follower 89 for clutch-shifter cams on drum 90 fast on shaft 80 and fast to rack-wheel 81. The pawl 82 is controlled to actuate or not actuate the rack-wheel 81 and shaft 80 and mechanism worked from shaft 80 by a chain-reading pawl-controlling rocker on shaft 93 having a finger piece 83a and the pawl-controller tail 83, the nose of pawl 82 being broad enough to slide on the tail 83 except when lifting motion by a lug on primary pattern C depresses tail 83 to let the pawl into contact with rack-wheel 81. The shape of tail 83 and the position of its center of motion are such as to permit the pawl to engage wheel 81 through a greater or less angular motion, according to the height of the lug on chain C. The rack-wheel 81 and shaft 80 must be moved through different angles at different times during each stocking; it is customary to provide tooth-depressions in wheel 81 at distances apart corresponding to these angular motions, the pawl-controller 83 being relied upon only to prevent too great a throw when tooth-depressions on wheel 81 for a succession of short motions are provided. A relatively large angle of motion is desirable on going on and coming off the heel and toe knitting, since during these motions automatic control of the motion change to or from reciprocation, the successive adjustment of driving speed, change of the positions of switch cams, yarn-feeding devices, stitch length devices, web-holder devices, the control of picking mechanism and other adjustments must be effected as a consequence of motion of shaft 80. Many of these adjustments in the machine referred to are derived from followers and connections to them worked by cams on a drum 120 geared at 121, 122, 123 to move with shaft 80. For certain special purposes the rotary system 80, 120, 121, 122, 123 may be moved independently of rack-wheel 81 by devices, not shown, to take short steps within an angle of advance by pawl 82 and rack-wheel 81 in time with the passage by the knitting cams of several particular segments of the needle cylinder; or to change the position of the needle cylinder angularly in respect to rotative position of

the shaft 32, 39 by special adjustment of clutch-shifter 92.

It will be observed that the sum of angular movements of substantial extent sufficient to work followers by cams of practicable shape capable of being made by shaft 80 during one revolution, representing one article made by the machine, is strictly limited. It is in fact insufficient for all of the adjustments required by desirable features to be incorporated in the article. For an example, in many types of stocking at heel or toe or elsewhere it is often desirable repeatedly and successively to narrow and widen by control of the operation of pickers or switch cams; motions of shaft 80 to control the pickers or move needle-cams for this purpose must take place within the angle of motion between operative shifts of the motion-changing clutch, and there is not room for any substantial motion of shaft 80 within this angle for more than one or two such adjustments. Heretofore good practice has avoided delegating such motions, which must be exact, to auxiliary pattern devices; heretofore mechanism has not been available to coordinate the control impulses of two or more pattern surfaces capable of the necessary effect in such a way as to secure an exact operative agreement between the several patterns; especially it has not been possible to provide for the manual resetting of the primary pattern without endangering coordinate operation of the main and auxiliary pattern surfaces and connections.

According to the present invention, the main pattern control represented by the shaft 80 and things driven by it, in turn controlled by the primary pattern surface C, may still be relied upon for all of its customary functions, but it is provided to supplement its indications by the operation from time to time of an auxiliary pattern surface and connections to the controllable agencies of the machine, or any desired number of them; it is also provided to prevent actuation of the main pattern device until the auxiliary pattern device shall have completed a predetermined cycle of operations; and it is also provided that the auxiliary pattern surface shall be held out of operation whenever the main pattern surface is in condition to operate, and while the primary pattern surface is being reset or manually adjusted.

For these and other purposes the auxiliary pattern may comprise a drum 150 conveniently mounted anywhere in relation to the driving devices for the machine, as shown, on a projecting end of the shaft 80, on which the drum 150 has freedom of motion limited by contact of a spring stop 151 in a bore in a dog 152 keyed on shaft 80 with opposite faces of interior teeth 153, 154 preferably formed on annular segments adjustably fastened in

an annular groove of the inner surface of drum 150. Drum 150 by this arrangement is free to move in respect to shaft 80 counterclockwise as viewed in Fig. 2 until by contact of stop 151 with tooth 154, further motion of drum 150 will also move shaft 80 and all of its connected parts. Shaft 80 and stop 151 are also free to move counterclockwise, Fig. 2, in respect to drum 150 until stop 151 encounters tooth 153, whereupon drum 150 is moved with shaft 80.

In order to provide for a self-limiting extent of motion of the main pattern, rack-wheel 81 for shaft 80 may be provided at 81^a 15 at a suitable angle from stop 151 with a relatively long blank interval between tooth depressions capable of being engaged by pawl 82, so that pawl 82, the stroke of which is fixed by the position of its driving stud 77 20 on sector 75, is incapable of further engagement with a tooth-depression of the rack-wheel until shaft 80 shall have been advanced slightly. When stopped upon reaching this position, the primary pattern surface C no 25 longer controls the further motion of main pattern shaft 80, since the pawl controller 83 may then be rocked without permitting any operative engagement of the pawl 82 and rack-wheel 81. The primary surface C may 30 be moved by hand, or the finger piece 83^a lifted without result whenever the main pattern 80 has come to this position. There may be more than one long space 81^a on wheel 81.

Actuation of drum 150 is depended upon, 35 through tooth 154, to cause the wheel 81 and shaft 80 to resume operation under control of the main pattern surface C. Rotation of drum 150 independently of its drive through stop 151 and tooth 153 may be utilized 40 through cams on it, suitable followers and connections, for pattern indications at times related to revolutions or reciprocations of the needle cylinder by providing a drive for drum 150, continuous or intermittent, related to motions of the needle cylinder, and effective only when motion of shaft 80 shall have stopped as described. As shown, drum 150 is moved by a ratchet wheel 160 integral 45 with or attached to drum 150 and hook pawl 161, divided at 162 for adjustment, having an elbow 163 carried around a member of the machine frame, and driven by a stud 164 radially adjustable on the hub of sector 75, and having a counterbalance spring 165 supporting its weight from the machine frame. Ratchet 160 has a tooth 160^a longer than the stroke of the pawl 161 adapted to reach the pawl, for example, just after stop 151 has encountered tooth 154. There may be more 55 than one tooth 160^a. Overthrow or unintentional motion of drum 150 is prevented by a brake plug 166 in a bore in a bracket 167 on the machine frame, urged by a spring 169 and screw 168 against the surface of drum 60 150.

When shaft 80 has stopped, it will be started by tooth 154 contacting with stop 151, whereupon drum 150 will stop with the pawl 161 on tooth 160^a. The angle of advance of drum 150 as racked forward by pawl 161 between these positions brings cams 170 for any desired pattern indications under suitable followers to actuate their connections.

For example, referring to Figs. 1 and 2, 75 there may be mounted on brackets 175, 175 under the bed plate of the operating part of the machine rock shafts 176 and 177 carrying at their right ends, Fig. 1, indicator arms 178 and 179 which may, if desired, be provided with screw adjustments at 180, 181 to adjust their relations to the shafts 176 and 177 respectively.

At the left side of the machine, Figs. 1 and 3, the shafts 176, 177 may carry suitable 85 lever arms for working connections to devices at the head of the machine. The connection from the shaft 176, for example, may be employed to operate picker controllers and/or switch cams, or cams having to do 90 with repeated or extra fashionings. As indicated in Figs. 1, 2, 3, 4 and 5, for this purpose a series of switch cams indicated generally at 280 and 281 in Fig. 4 may be arranged to be operated by vertical motions 95 of a finger 182 carried by a collar fast on the top of a thrust rod 183, Figs. 3 and 4, also carrying an arm 286 for rocking a widening picker axis 287. Now normally the rod 183 may be given its usual motions for ordinary 100 knitting by cams 184 on the cam drum 120 driven in unison with the cam shaft 80, acting through a follower 185 pivoted at 186 and working a lever 187 against a spring 188. But for the present purposes it may be desirable not to move drum 120 for extra or special pattern indications, and the shaft 176 and the pattern indications of the drum 150 may be relied upon instead, in addition to but not in exclusion of the effect of cams 184 110 on drum 120. For example, shaft 176 may carry an arm 277 having a pin 278 extending under the lever 187.

Motions of the shaft 176 are by this means 115 competent to lift the thrust rod 183 independently of the position of the drum 120 and cams 184, to extents greater or less than the effect of cams 184, and at times controlled by drum 150 during inactivity of shaft 80.

Similarly, for purposes such as those above suggested, it may be desirable to act upon the needles between their passages of the stitch cams to depress a segment of or all of the needles or to elevate a segment of or 125 all of the needles, and to do this without recourse to necessary motion of main pattern shaft 80. There is generally indicated in Fig. 4 at 190 a depressing cam and at 191 an elevating cam. These may be so mounted 130

that one of them approaches the needle cylinder as the other moves away from it. Cam 191 may be carried by an arm 192 pivoted at 193 and having an adjustable connection at 194 with a carrier arm 195 pivoted at 199. A linkage of this type produces the result of connecting the cams so as to move one radially inward on outward motion of the other. As illustrated, the arm 192 may be operated by an extension 200 having a fork taking over an eccentric pin 201 of a vertical rock shaft 202 having an arm 203, Fig. 3, operated by a link 210 loosely pivoted at 211 to an arm 205 and at 204 to arm 203 and controlled by motion of arm 205 with the shaft 177. In a preferred form, the time of one extent of the motion of the vertical rock shaft 202 is controlled from the drum 120, for example by cams on the end of the drum 120 shown at 206. A pin 207 adjustable on the arm 205 projects into the path of the cam 206 from which path it may be removed or into which path it may be placed by operation of the shaft 177. If desired, motions by the shaft 177 may be relied upon solely to operate such a connection as the vertical rock shaft 202 and the cams operated by it. Motion by cam 206 acting on pin 207 is in a direction to lift indicator 179, Fig. 2, away from the auxiliary drum 150.

It will be observed that connections such as the shafts 176 and 177, or any other type of connection, to any kind of device requiring to be positioned or adjusted at a particular time, may be relied upon to transmit the repeated effect of cams on the drum 150, and that during a cycle of motions of the pattern devices and connections the main pattern surface is not only not operated by but is prevented from being operated by the primary pattern surface C; whereas the auxiliary pattern drum 150 is held immobile until brought into action by the main pattern shaft 80 as controlled by the primary pattern surface C for another cycle of its operations.

I claim:

1. Pattern mechanism for textile machines having therein in combination a primary pattern surface and a main pattern surface, and means controlled by the primary pattern surface for actuating the main pattern surface; an auxiliary pattern surface and means for advancing the same adapted to be brought into operation by a part moving with the main pattern surface, and means for preventing actuation of the main pattern surface during advance of the auxiliary pattern surface by said means for actuating the same.

2. Pattern mechanism for textile machines having therein in combination a primary pattern surface and a main pattern surface, and means controlled by the primary pattern surface for intermittently moving the main pattern surface, an auxiliary pattern surface and means for advancing the same adapted to be

brought into operation by a part moving with the main pattern surface, means preventing actuation of the main pattern surface during further actuation of the auxiliary pattern surface, and means moving with the auxiliary pattern surface for initiating further actuation of said main pattern surface.

3. Pattern mechanism for textile machines having in combination a main pattern shaft and means for driving said shaft, means thereon for positioning operative agencies of the machine at times, an auxiliary pattern mechanism and an operating connection worked thereby, and means for driving said auxiliary pattern mechanism independently of said pattern shaft, said means for driving said shaft and for driving said auxiliary pattern mechanism severally including means causing cessation of further motion caused by said driving means respectively, said pattern shaft and said auxiliary pattern mechanism severally having thereon means each for causing to be initiated a further period of driving actuation of the other pattern.

4. Pattern mechanism for textile machines having in combination a main pattern shaft and means for driving said shaft, means thereon for positioning operative agencies of the machine at times, an auxiliary pattern mechanism and an operating connection worked thereby, and means for driving said auxiliary pattern mechanism independently of said pattern shaft, said means for driving said shaft and for driving said auxiliary pattern mechanism severally including means causing cessation of further motion caused by said driving means respectively, said pattern shaft and said auxiliary pattern mechanism severally having thereon means each for moving the other to cause its driving means to initiate a further period of driving actuation.

5. Pattern mechanism for textile machines having in combination means for driving a driven element of the machine in a constant rotary direction and for driving said element reciprocally at times, a main pattern shaft and means for rotating said shaft intermittently, means thereon for actuating a part to cause change from one said kind of motion to another, an auxiliary pattern mechanism and operating connections to be worked thereby during reciprocal motion of the said driven element, and means for moving said auxiliary pattern mechanism independently of said pattern shaft, said means for rotating said shaft and for moving said auxiliary pattern mechanism severally including means causing cessation after a predetermined motion thereof of further motion of said pattern means, said shaft and said auxiliary pattern mechanism severally including parts each operating on the other to initiate a further period of actuation.

6. Pattern mechanism for textile machines having therein in combination a primary pat-

tern surface and a main pattern surface and means controlled by the primary pattern surface for actuating the main pattern surface through a predetermined extent of motion; an auxiliary pattern surface and means for advancing the same adapted to be brought into operation by a part moving with the main pattern surface and adapted initially to advance said auxiliary surface prior to cessation of its extent of motion; means preventing actuation of said main pattern surface during prior actuation of the auxiliary pattern surface, and means moving with said auxiliary surface for advancing the main pattern surface to initiate an extent of its motion.

7. Pattern mechanism for textile machines having therein in combination a primary pattern surface and a main pattern surface, means for continually actuating the primary pattern surface, a controller and means controlled thereby on motion of said primary pattern surface for intermittently actuating the main pattern surface; means moving with said main pattern surface for rendering control by said controller ineffective, an auxiliary pattern surface and means for advancing the same during cessation of motion of said main surface adapted to be brought into operation by a part moving with the main pattern surface.

8. Pattern mechanism for textile machines having therein in combination a primary pattern surface and a main pattern surface, a controller adapted to be positioned by said primary pattern surface and a pawl controlled by said controller for intermittently actuating the main pattern surface at predetermined times, an auxiliary pattern surface and means for advancing the same adapted to be brought into operation by a part moving with the main pattern surface, means preventing actuation of the main pattern surface by said pawl during actuation of the auxiliary pattern surface, and means moving with the auxiliary pattern surface for withdrawing said actuation preventing means to initiate further actuation of said main pattern surface.

9. Pattern mechanism for knitting machines having in combination a main pattern shaft and means for rotating said shaft intermittently, means thereon for positioning operative agencies of the machine at times, an auxiliary pattern mechanism and an operating connection worked thereby, and means for driving said auxiliary pattern mechanism independently of said pattern shaft, said means for rotating said shaft and for driving said auxiliary pattern mechanism severally including means causing cessation of further motion of said parts, said shaft and said auxiliary pattern mechanism severally including parts each for causing the other to initiate a further period of actuation, and means for working said operating connection

moving in unison with said main pattern shaft.

10. Pattern mechanism for knitting machines having in combination means for driving a driven element of the machine in a constant rotary direction and means for driving said element reciprocally at times, a main pattern shaft and pattern devices moving in unison therewith, and means for rotating said shaft intermittently, means thereon for actuating a part to cause change from one of said kinds of motion to another, an auxiliary pattern mechanism and operating connections to be worked thereby during reciprocal motion of said driven element, and means for moving said auxiliary pattern mechanism independently of said pattern shaft, said means for rotating said shaft and for moving said auxiliary pattern mechanism severally including means causing cessation after a predetermined motion thereof of further motion of said pattern means, said shaft and said auxiliary pattern mechanism severally including parts each for moving the other to initiate a further period of actuation, said operating connections having a part positioned and adapted to be operated by said main pattern devices, whereby said connections are operated at different times by said main and said auxiliary pattern devices severally.

11. Pattern mechanism for textile machines having therein in combination a primary pattern surface and a main pattern surface and means controlled by the primary pattern surface for intermittently actuating the main pattern surface; an auxiliary pattern surface and means for advancing the same, said means for actuating the main pattern surface being adapted to be brought into operation and prevented from further operation by a part moving with the main pattern surface, said part being positioned to prevent actuation of the main pattern surface during actuation of the auxiliary pattern surface.

12. Pattern mechanism for textile machines having therein in combination a primary pattern surface and a main pattern surface and means controlled by the primary pattern surface for intermittently actuating the main pattern surface; an auxiliary pattern surface and means for advancing the same, said means for actuating the main pattern surface being adapted to be brought into operation and prevented from further operation by a part moving with the main pattern surface, said part being positioned to prevent actuation of the main pattern surface during actuation of the auxiliary pattern surface, and means moving with said auxiliary pattern surface for positioning said part to permit further actuation of said main pattern surface after a predetermined motion of said auxiliary pattern surface.

13. In a knitting machine having operative agencies at the knitting head for determining the motions of needles, and devices for causing rotatory and reciprocatory relative motion between a needle-carrier and said operative agencies, the combination of a main pattern surface adapted to be operated at times during said rotatory motion, and an auxiliary pattern surface adapted to be operated at times during said reciprocatory motion, of transmitting connections between said pattern surfaces severally and one of said agencies adapted to be operated from and by either of said pattern surfaces. 70
14. In a knitting machine having operative agencies at the knitting head for determining the motions of needles, and devices for causing rotatory and reciprocatory relative motion between a needle-carrier and said operative agencies, the combination of a continually operated primary pattern surface, a main pattern surface adapted to be operated at times controlled by said primary surface during said rotatory motion, and an auxiliary pattern surface adapted to be operated at times during said reciprocatory motion, of transmitting connections between said main and auxiliary pattern surfaces severally and one of said agencies adapted to be operated from and by either of said main and auxiliary pattern surfaces, and means on said main pattern surface for predetermining change of rotatory and reciprocatory motion each to the other kind of motion. 75
15. In a knitting machine pattern mechanism, the combination of a main pattern shaft and an auxiliary pattern drum, means rotating with each of said parts adapted to engage and rotate the other in one direction of relative motion between them, means severally for actuating said drum and shaft severally adapted to be brought to an inoperative state at a predetermined rotatory position of said drum and said shaft respectively, each after an angle of advance including a position at which the said means adapted to engage has engaged and moved both said drum and said shaft, whereby alternative motion of said drum and shaft severally each by its own actuating means through a predetermined angle of motion is caused. 80
16. In combination, in a pattern mechanism for knitting machines, a main pattern surface and an auxiliary pattern surface, operating means for said pattern surfaces, controllable agencies adapted to be positioned differently at different times during operation of the machine, a system of transmitting connections each adapted to be moved by one of said pattern surfaces to position one of said agencies, and pattern transmitting devices adapted to be moved by the other pattern surface to operate said connections, said pattern surfaces severally 85
